UNITED STATES PATENT OFFICE.

HENRY L. WALLACE, OF WALLINGFORD, CONNECTICUT.

DESIGN FOR A SPOON, FORK, OR SIMILAR ARTICLE.

52,834.

Specification for Design.

Patented Dec. 31, 1918.

Application filed June 6, 1918. Serial No. 238,597. Term of patent 7 years.

To all whom it may concern:

Be it known that I, **HENRY L. WALLACE**, a citizen of the United States, residing at Wallingford, in the county of New Haven and State of Connecticut, have invented a new, original, and ornamental Design for a Spoon, Fork, or Similar Article, of which the following is a specification, reference being had to the accompanying drawing, forming a part thereof.

Figure 1 is a face view of the spoon.

Fig. 2 is a detail perspective view of the end of the handle.

I claim—

The ornamental design for a spoon, fork or similar article, as shown.

Wallingford, Conn., June 3, 1918.

HENRY L. WALLACE.
